(57) **CLAIM**

The ornamental design for a slide clamp, as shown and described.

DESCRIPTION

FIG. 1 is a front, top, and right-side perspective view of the slide clamp, which may be used to occlude a fluid line within the slot, showing our new design;

FIG. 2 is a front elevation view thereof;

FIG. 3 is a back elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is a front, top, and right-side perspective view of another embodiment of a slide clamp, showing our new design;

FIG. 9 is a front elevation view thereof;

FIG. 10 is a back elevational view thereof;

FIG. 11 is a right-side elevational view thereof;

FIG. 12 is a left-side elevational view thereof;

FIG. 13 is a top plan view thereof; and,

FIG. 14 is a bottom plan view thereof.

The ornamental design which is claimed is shown in solid lines in the drawings. The broken lines show portions of the slide clamp that form no part of the claimed design.
